(57) **CLAIM**

The ornamental design for culinary cutting blade, as shown and described.

DESCRIPTION

FIG. 1 is a front view of the culinary cutting blade embodying the new design;

FIG. 2 is a top view thereof;

FIG. 3 is a right side view thereof, the left side being a mirror image thereof; and,

FIG. 4 is an enlarged perspective view thereof.

FIGS. 1-4 show features of a culinary cutting blade in phantom lines. These features are shown for environmental purposes and do not form any part of the claimed design. Further, the phantom lines immediately adjacent the solid-line portions of the design form the boundary of the design, with the phantom lines forming no part of the claimed design.
